UNITED STATES PATENT OFFICE.

LOUIS HORNBERGER, OF BRIDGEPORT, CONNECTICUT, ASSIGNOR OF ONE-HALF TO THEODORE C. GAUSS, OF KINGSTON, NEW YORK.

DESIGN FOR A CLOCK-CASE.

SPECIFICATION forming part of Design No. 36,181, dated December 30, 1902.

Application filed October 18, 1902. Serial No. 127,124. Term of patent 7 years.

To all whom it may concern:

Be it known that I, LOUIS HORNBERGER, a citizen of the United States, residing at No. 144 Grove street, Bridgeport, Connecticut, have invented and produced a new, original, and ornamental Design for a Clock-Case, of which the following is a specification.

The accompanying drawings show in Figures I and II, respectively, a front and side elevation of a clock-case embodying my design. 1 designates the face of the case, which is pierced by a circular aperture 2, bordered by vertical corner-scrolls 3, which extend to the foot of the case. Below and above the aperture are representations of wave-crests 4.

Rising from these and above the aperture is represented an undraped youthful figure 5. On the side 6 of the case is a curved panel 7, on the lower portion of which is shown a conventional foliation.

20

The essential feature of my design is the pierced front, whose undulations represent wave-crests and the figure rising therefrom.

What I claim is—

The ornamental design for a clock-case or 25 like article herein shown and described.

LOUIS HORNBERGER.
